US00D986522S

(12) **United States Design Patent** (10) Patent No.: **US D986,522 S**
(45) Date of Patent: **** May 16, 2023**

(54) **GRILL SCRAPER**(71) Applicant: **Thompson Brothers & Company, LLC**, Oakdale, MN (US)(72) Inventors: **Jason S. Thompson**, Woodbury, MN (US); **Andrew N. Stadick**, Woodbury, MN (US); **Nathan A. Thompson**, North Saint Paul, MN (US)(73) Assignee: **Thompson Brothers & Company LLC**, Oakdale, MN (US)(**) Term: **15 Years**(21) Appl. No.: **29/789,307**(22) Filed: **Sep. 15, 2021****Related U.S. Application Data**

(60) Continuation-in-part of application No. 29/723,101, filed on Feb. 4, 2020, now Pat. No. Des. 933,323, which is a continuation of application No. 29/645,240, filed on Apr. 24, 2018, now Pat. No. Des. 874,774, which is a division of application No. 29/599,585, filed on Apr. 5, 2017, now Pat. No. Des. 846,218.

(57)

CLAIM

We claim the ornamental design for a grill scraper, as shown and described.

DESCRIPTION

FIG. 1 is a perspective view of our design for a grill scraper; FIG. 2 is a left side view thereof, the right side being identical thereof;

FIG. 3 is a top view thereof;

FIG. 4 is a bottom view thereof;

FIG. 5 is a back view thereof; and,

FIG. 6 is a front view thereof.

The broken lines in the drawings depict features of the grill scraper that form no part of the claimed design.

1 Claim, 3 Drawing Sheets
